MODEL AIRPLANE PROPELLER

Frank J. Merz, Jr., and George B. Merz, Seattle,
Wash.

Application September 20, 1937, Serial No. 164,663

1 Claim. (Cl. 170—173)

Our invention relates to model airplane propellers, and more particularly to a miniature airplane propeller that is transversely severed at its central hub portion, together with means for securing the two severed parts together in the form of a butt joint at the center of the hub.

The objects of the invention, in making a propeller in equal parts that are secured together by a butt joint at the center of the hub, are that, when one of the propeller blades is broken, same may be replaced at less expense than would be incurred by replacement of the entire propeller. In order to completely effect this saving of expense, we have devised a simple, effective and inexpensive means for securing together the severed parts of the propeller.

It will be expressly understood that our invention is solely intended for use in connection with model and toy or other miniature airplanes or propellers. It is not intended for use on full size propellers and would doubtless be of no practical value or utility for such use. Model and toy airplane propellers are usually made of wood or light metal such as aluminum, and the objects of our invention relate exclusively to such propellers. It will also be understood that model airplanes are miniature planes that are flown by youngsters as a source of amusement and skill, and a saving of money, although small in amount, means much to them.

In the drawing:

Figure 1 is a view in front elevation of a model or toy airplane propeller that is severed and connected together at its center, and also showing one of the propeller blades broken away in dotted lines;

Fig. 2 is a view in central transverse vertical section taken substantially on a broken line 2—2 of Fig. 1; and

Fig. 3 is a detail view in perspective showing one member of the securing means.

Referring in detail to the drawing wherein like reference numerals indicate like parts in the several views, the numerals 5 and 6 respectively designate the two blades of a model or toy airplane propeller. These two blades are joined together at their center hub portion 7 which is severed centrally and transversely as shown at 8 in Fig. 1. The propeller may either be made as a single unit and severed afterward, or it may be made in two equal parts originally as desired.

When the hub portion 7 of the propeller is severed centrally, two equal faces are formed,

one of which is shown in elevation at 9 in Fig. 2 of the drawing. When the two parts of the propeller are joined, these two faces are placed or fitted together to form a butt joint at 8 as will be understood. The usual hole 10 extends centrally through the hub portion 7, half of same being in each severed part of the hub. Said hole forms a journal bearing for a propeller shaft 11 which extends forward from the nose 12 of a model airplane which is not shown.

The simple means for securing the two severed parts of the propeller hub 7 together is the most important part of the invention. Said means may consist of a pair of disc plates 13 each having an annular flange 14 extending at right angles from its periphery. A hole 15 is centrally provided in each disc plate for reception of the shaft 11. The hub 7 has an annular groove 16 cut in both its front and rear sides concentric with the hole 10, half of said groove being disposed in each severed part of the hub. These grooves are adapted to snugly receive the flanges 14 of the disc plates 13.

In the assemblage of the severed parts of the propeller, their severed faces 9 are placed together in abutment. The flanges 14 of each of the disc plates 13 are then inserted into the annular grooves 16 in both the front and rear sides of the hub 7. The disc plates are both pressed inward, their flanges snugly fitting into the grooves, and the two parts of the propeller are thus held securely together. The propeller may then be installed on the shaft 11 with the rear disc plate 13 bearing against an annular shoulder 17 formed on said shaft, and a nut 18 may be installed on the outer threaded end of the shaft and bearing against the front disc plate 13 as clearly shown in Fig. 2 of the drawing.

We claim:

An article of manufacture comprising a miniature propeller having a hub with a center hole therein, said hub centrally and transversely severed to form equal parts with abutting faces fitted together, a groove formed around the hole in the hub on both the front and rear sides thereof, a pair of plates each having a right angular edge flange, and the flange of each plate fitting into the groove of the hub on each of its respective sides for the purpose of securing the severed parts of the propeller together in the form of a butt joint and as a unit in itself.
